DESIGN FOR A CAP

Rose Feintuck, New York, N. Y.

Application January 26, 1939, Serial No. 82,605

Term of patent 3½ years

To all whom it may concern:

Be it known that I, Rose Feintuck, a citizen of the United States, residing in New York city, in the county of New York and State of New York, have invented a new, original, and ornamental Design for a Cap, of which the following is a specification, reference being had to the accompanying drawing, forming part thereof.

Fig. 1 is a perspective view of a cap showing my design,

Fig. 2 is a rear view of the cap shown in Fig. 1,

Fig. 3 is a side view thereof,

Fig. 4 is a plan view in extended position of same.

The characteristic feature of my design resides in the combination on the specific cap disclosed of the specific floral trim arranged on the front of the brim as shown.

I claim:

The ornamental design for a cap, substantially as shown and described.

ROSE FEINTUCK.
